UNITED STATES PATENT OFFICE.

BERTRAND A. PARKES, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA.

SINGEING-MACHINE.

1,170,183.

Specification of Letters Patent.

Patented Feb. 1, 1916.

Application filed April 1, 1915. Serial No. 18,522.

To all whom it may concern:

Be it known that I, BERTRAND A. PARKES, of Philadelphia, in the county of Philadelphia and State of Pennsylvania, have invented certain new and useful Improvements in Singeing-Machines, whereof the following is a specification, reference being had to the accompanying drawings.

My invention relates to singeing machines for singeing hosiery or similar articles, of the class in which a succession of article holders are successively carried into operative relation to singeing burners.

It is the object of my invention to economize combustible by so controlling its supply to the singeing burners that an effective singeing flame is only created as each article to be singed is successively carried by its holder into proximity to the burners, and when it has passed from the region of the burners, the supply of combustible is reduced to only enough to perpetuate the flame. To this end the control of the supply of gas to the burner is made conditional upon the presence or absence of an article to be singed upon each holder so that in case a holder does not carry an article to be singed, the increase of the gas supply does not occur. This I accomplish by means of an electric circuit, including an electro-magnet, whereby the means for increasing the gas supply are rendered inoperative by the closing of the circuit, which circuit is completed through contact between the traveling holder, and a fixed contact, so that if the holder carries an article, it is insulated from the contact and the circuit is not closed, under which condition the travel of the holder effects the required increase in the jet, as the article to be singed approaches it.

In the accompanying drawings, Figure I, shows in side elevation a machine containing the essential operative parts of my device. Figs. II, III, and IV, are respectively a plan view, a side view and a front view of the means for controlling the supply of combustible for the singeing jets. Figs. V, and VI, are respectively a side elevation and a sectional plan of the fixed contact of the electric circuit. Fig. VII, is a sectional view along the line VII, VII, Fig. III. Fig. VIII, is a side view of the roller seen in Fig. V, from the opposite side. Fig. IX, is a sectional view along the line IX, IX,

Fig. V. Fig. X, is an enlarged view of the cam incline by means of which the decrease of the jet is occasioned. Fig. XI, is a similar sectional view along the line XI, XI, of Fig. I. Fig. XII, is an enlarged view of the tail piece of one of the holders.

Referring to Fig. I, the spider frame 1, rotates upon the shaft 2. Each arm of this spider frame carries a holder 3, set off slightly from the plane of the spider frame, and curved so as to occupy a peripheral relation to the rotating frame. Each holder carries a tail piece 4, which is shown more in detail in Fig. XII, and which is set in adjustable relation thereto, by the set screws 5, which hold the groove of the tail piece 60 upon the tongue 6, which projects from the bottom of the holder. The tail piece carries a small roller 7, projecting into the plane which contains coöperating parts of devices for controlling the supply of gas to the 65 burners, and it is the properly timed contact of this roller 7, with the controlling devices hereafter to be described, that effects the operation of my machine to the end which I have described.

The burner tubes 10, 10, and also spark-extinguishing rolls 9, 9, are set on either side of the path of the holder 3. The tubes are perforated for the production of singeing jets by burning a mixture of gas and air, 85 supplied to the burner tubes by a mixer 11, which receives gas from the pipe 12, and air from the pipe 13. Both of these pipes have interposed within them control valves 14, 14, which are simultaneously operated by rotation of a rock shaft 15, to which the valve spindles are attached by the coupling collars 8, 8. Upon this rock shaft is set the arm 16, pivotally connected by a link 17, with a bracket 18, set upon the rod 19, which 90 has a lengthwise motion for the control of the valves for the supply of gas and air to the burners, the downward motion of the rod tending to increase the supply of gas, and the upward motion tending to decrease 95 it. The extent of this motion is limited so that at one end of its play the burners receive the full amount of gas required to produce an effective singeing jet, while at the other end of its play, the supply is so reduced as to leave only that slight amount required to perpetuate the flame. If preferred, the main gas flame of the perforated

burners may be extinguished absolutely, but in that case a small "pilot light" is used for relighting the main flames when the gas is again turned on.

- 5 Lowering of the flame is occasioned by contact of the roller 7, with the cam incline of a cam piece 20, set upon a sector bar 21, which is supported by pivotal connection with the link 22, pivoted to the fixed piece 10 23, forming part of the frame of the machine. The sector bar 21, is also pivotally connected with the lever 24, pivoted centrally on the fixed bracket 25, and at its other end to the lower end of the rod 19. 15 By the coöperation of these parts, whenever one of the rollers 7, comes into contact with the cam piece 20, the rod 19, is elevated so as to reduce the supply of gas to a minimum. This is timed to coincide with the completion 20 of the singeing of an article held by the holder which follows that one to which is attached the roller 7, which effects the controlling operation, and the proper timing is secured by the adjustment of the cam 25 piece 20, upon the sector bar 21, for which purpose it is slidably mounted thereon, and capable of being set in any desired position by the set screw 28, as shown in Fig. XI.

The increase of the flame is effected by 30 contact of the roller 7, with the inclined upper edge of a pivoted cam-piece 30, which normally lies in the path of the roller. This cam-piece 30, forms part of a larger swinging bracket 31, pivoted at 32, and carrying 35 an arm 33, connected by a link 34, with the rod 19, so that contact of the roller 7, with the cam-piece 30, effects rotation of the bracket 31, sufficient to depress the rod and thereby increase the supply of gas. This 40 contact is also so timed that normally the contact of one of the rollers 7, with the cam-piece 30, occurs just before the holder is about to pass into the region of the burners, which is the position in which the parts are 45 shown in Fig. I.

By the coöperation and properly timed arrangement of the parts thus far described, successive contact of each roller 7, with the controlling apparatus described, increases 50 and decreases the supply of combustible so as to produce an effective singeing flame during, but only during, the passage of a holder between the burners. But it frequently happens that the attendant fails to 55 place an article to be singed upon each of the holders, as they rotate, and it is an end of my invention to supply a further control whereby the passage of a holder not containing any article into the region of the 60 singeing burners, shall fail to effect the increase in the supply of gas which would otherwise occur. This I accomplish as follows: An electric circuit 40, includes a brush 41, pressing against the metal ring 65 42, on the side of an insulated roller 43.

This roller is provided with a peripheral metallic contact 44, which is electrically connected to the ring 42, and also a flattened surface 45, which is not so electrically connected. The roller 43, is mounted upon a bracket 46, swinging upon an arm 47, set upon plate 48, which is secured to the fixed framework of the machine, with capacity for vertical adjustment by slot and bolt connection, as shown in Figs. I and V. A further slot and bolt adjustment at right angles to the above is provided, between the plate 48, and the arm 47, (see Fig. V), so that the position of the roller in relation to the line of rotation of the holders may be 70 controlled with great accuracy. The roller 43, is further given a yielding capacity by means of its pivotal mounting on the arm 47, which carries a lug 49, which affords a resistance point for the coiled spring 50, 75 which exerts tension upon the arm 52, which is an integral part of the swinging bracket 46, and thus tends to hold the bracket in its horizontal position as shown in Fig. I.

Each of the holders 3, is constructed of 90 conductive material and the circuit is completed through the metal framework of the machine, and the conductor 63, through the coils of two electro-magnets 64, and thence by the conductor 65, to the battery 66. When 95 thus closed, the electro-magnets attract the cam-piece 30, the lower edge of which is pivoted to piece 31, by the pivot 69, and draw it laterally out of the plane in which the roller 7, rotates. Accordingly, provided no article is carried by the holder 60, the making of a circuit as thus described, prevents the passage of the roller 7, from effecting any increase of the supply of gas. If, however, an article of textile fabric, as 100 for example, a stocking, as indicated at 60, Fig. I, has been stretched upon the holder 3, the fabric acts as an insulator to prevent the contact of the surface of the holder with the roller 43, and accordingly the contact 105 of the roller 7, with the part 30, occurs with the corresponding control of the valve supplying gas.

In order to limit the making of the circuit to that time when alone it is useful, the 110 roller 43, is limited in its capacity for rotation by a stop 70, upon reaching which the flat side of the roller, which is not in the circuit, is presented toward the passing holder. Even though the article to be 115 singed is of small extent, covering only the upper end of the holder, it effects the required insulation long enough to turn the flat side of the roller toward the holder, whereupon insulation is no longer necessary.

The roller 43, is normally maintained in the position shown in the drawings by means of a stop lug 75, which engages one of the side arms of the bracket 46, and is main- 120 125 130

tained in this position by a coiled spring 76, best shown in Fig. VI. This spring also serves to return the roller to its normal position after being partially rotated by contact with the holders.

The tail pieces 4, herein shown, are only employed to adapt the machine for the singeing of half hose. In the singeing of full hose, the rollers 7, are attached directly to the sides of the holders 3. The functions of their rollers are, however, the same in either case, the additional length afforded by the extensions serving only to further limit the period for the full gas supply in accordance with the article under consideration.

I have spoken throughout the specification and claims of increasing and decreasing the supply of combustible by the controlling means described. It will, of course, be understood that the supply of combustible may be decreased to the point of extinction of the flame provided well-known means for re-ignition, such as a pilot light, are provided.

Having thus described my invention, I claim:

1. In a machine of the class described, the combination of holders capable of carrying singeable articles; singeing burners; means for carrying the holders successively into operative relation to the burners; means for increasing the supply of gas to the burners when a holder carrying an article approaches the region of the burners, and for decreasing the same when the holder leaves said region; and means whereby the approach of a holder carrying no article to be singed occasions no increase in the gas supply.

2. In a machine of the class described, the combination of holders capable of carrying singeable articles; singeing burners; means for carrying the holders successively into operative relation to the burners; means whereby the approach to the burners of a holder carrying an article occasions a temporary increase of the flame of the burners, and means whereby a holder not carrying such an article is prevented from thus affecting the flame, said means comprising an electric circuit, with an electromagnet, whereby the flame increasing means are rendered inoperative by the closing of the circuit, which is completed by contact of a fixed element with a passing holder, unless said holder carries an article which effects insulation of the holder from the fixed element.

3. In a machine of the class described in

which the approach of a holder to the singeing burners automatically occasions a temporary increase of the singeing flame; means for preventing the holder from effecting this, including an electric circuit which is completed by contact of a traveling holder with a fixed contact point, and also includes an electromagnet which when energized by the circuit, renders the flame increasing means inoperative, and means whereby the presence of an article to be singed upon the holder prevents the closing of the circuit between the fixed contact point and the holder.

4. In a machine of the class described, the combination of a rotating frame with a succession of holders mounted thereon; singeing burners in proximity to which the rotation of the frame successively carries the holders; a valve for determining the supply of gas to the burners; a projection in fixed relation of said rotating frame; a cam which is normally in position to be struck by said projection as it rotates with the frame; connections whereby said cam when thus struck actuates the valve to increase the supply of gas to the burner; and means whereby a holder carrying no article to be singed moves said cam out of the plane of the rotating projection at the time when it would otherwise be struck thereby, substantially as described.

5. In a machine of the class described, in which the supply of gas to the singeing burners is temporarily increased during the passage of an article to be singed between said burners; an electric circuit including electromagnets which by their action upon closing of the circuit prevent such increase of the flame, said circuit including the metal shod surface of the holder and the metal shod segment of a roller, mounted in fixed relation to the machine, with which the surface of the holder comes in contact and completes the circuit, unless its metal shod surface is insulated by the presence thereon of a singeable article, said roller including also a flattened non-conducting segment which prevents further rotation of the roller, and, therefore, possible closing of the circuit until the holder has passed away from the region of the roller.

In testimony whereof, I have hereunto signed my name at Philadelphia, Pennsylvania, this twenty-ninth day of March, 1915.

BERTRAND A. PARKES.
